UNITED STATES PATENT OFFICE

2,449,496

ELECTRICAL CONNECTION

Frank J. Matan, Gary, Ind.

Application March 31, 1943; Serial No. 481,342

2 Claims. (Cl. 287—64)

1.

This invention relates to improvements in electrical connections.

The primary object of this invention is the provision of an improved terminal connector for electrical parts such as cables, resistors, condensers, etc., which will enable the formation of an electrical connection between several parts without the use of solder, welds, screws or other foreign parts and expedients.

A further object of this invention is the provision of an electrical connection comprising a pair of terminal portions having readily assembled interfitting conductor means.

Other objects and advantages of this invention will be apparent during the course of the following detailed description.

In the accompanying drawing, wherein for the purpose of illustration is shown a preferred embodiment of the invention,

Figure 1 is a perspective view of an electrical part, such as a resistor, having the improved terminal connector means at the ends thereof.

Figure 2 is a fragmentary perspective view of two electrical parts such as a resistor and a condenser showing the improved terminal portions thereof interconnected.

Figure 3 is a transverse cross sectional view taken substantially on the line 3—3 of Figure 2.

Figure 4 is a cross sectional view similar to Figure 3 but showing the application of a protective lacquer or other plastic upon the terminal portions of the electrical parts at the electrical terminal connections.

In the drawing, wherein similar reference characters designate corresponding parts throughout the several views, the letter A may generally designate a resistor or other electrical part or appliance having the improved terminal portions 11 and 12 connected thereupon. These terminal portions 11 and 12 are preferably identical. Each of them consists of a thin strip or band of easily bendable sheet metal which is of course a terminal for the vital parts of the electrical appliance. The strips 11 and 12 are preferably thin, wide and flat, altho this conformation may be departed from if found necessary. Each terminal portion 11 and 12, along the opposed longitudinal edges thereof, is recessed or socketed at 15, 16 and 17; the recesses 15, 16 and 17 being in opposed relation as shown in Figure 1. These recesses are of uniform depth, width and height, and reduce the width of the strip to a thin section 20 between the opposed recesses. These recesses 15, 16 and 17 furthermore divide the strip into opposed sets of bendable

clamping teeth or fingers 22, 23 and 24, which are of uniform thickness, width and depth.

In the use of the improved terminal portion, the electrical parts to be connected, whether they be cables, resistors, condensers, or other electrical appliances, are assembled so that the terminal portions of the two parts, such as shown in Figure 2, are in abutment and overlapping relation with the teeth 22, 23 and 24 of one terminal part in position opposite the recesses 17, 16 and 15 respectively of the other terminal part. The clamping finger portions 22, 23 and 24 of one terminal portion are then bent thru the recesses of the other terminal part and overlap at the opposite side of the last mentioned terminal portion and then the finger portions of the last-mentioned terminal portion are likewise bent thru the recesses of the first terminal portion and clamped at the opposite side of the said terminal portion. The finger portions are thus overlapped at opposite sides of the thin strips 20, in the manner shown in Figure 2. This insures that the two electrical parts, such as a resistor and condenser A and B respectively, as shown in Figure 2, will be securely connected together with an electrical terminal connection which is foolproof. Due to the fact that the strips are broad and relatively thin, there can be no lateral turning movement between the terminals of the two connected parts, and there can be no endwise movement because the clamping fingers exactly fit in the recesses.

In Figure 4 I have shown a coating 30 of lacquer, synthetic resin paste or other plastic applied upon the interconnected terminal portions so as to completely coat the same and protect it. This assists in the maintenance of the connection, rendering the same safe from deterioration as a result of atmosphere variations and also additionally insuring the tightness of the connecting terminal portions.

Various changes in the shape, size and arrangement of parts of the connector and in the application of the same to any variety of electrical parts, etc., may be made to the form of the invention herein shown and described, without departing from the spirit of the invention or scope of the claims.

I claim:

1. In an electrical connection, the combination of a pair of parts having electrically operatively connected terminal straps, each of said straps being of thin, wide, flat electrically conductive metal including a flat body portion with uniformly spaced bendable clamping fingers along the opposed longitudinal side edges thereof in directly

opposed pairs, the terminal straps being so arranged when connected that the fingers of each terminal portion are bent in interfitting relation exactly in snug fitting relation between adjacent fingers of the other terminal portion and over the opposite side of the body of said other terminal portion.

2. An electrical connector and the like comprising a pair of relatively thin, wide, flat bendable metal straps, each of said straps from the extreme ends thereof being provided with a plurality of opposed pairs of fingers projecting in spaced relation from the opposite edges thereof, the spaces between the adjacent pairs of fingers along each edge being entirely unobstructed and the fingers being of uniform width and the unobstructed spaces between adjacent fingers along each edge of each strap being of uniform width, the two straps in connection being disposed side by side with the fingers of each strap opposite the spaces between the fingers of the other strap and with the fingers of one strap bent thru the spaces of the other strap over the side of the said other strap, and the fingers of the last mentioned strap bent thru the spaces of the first mentioned strap

and over the opposite side of the first mentioned strap.

FRANK J. MATAN.
